FASTENING-INSERTING MACHINE

Frank E. Stratton, Beverly, Mass., assignor to
United Shoe Machinery Corporation, Flem-
ington, N. J., a corporation of New Jersey

Application December 30, 1941, Serial No. 424,858

6 Claims. (Cl. 12—42)

My invention relates to machines by which fastenings are inserted in shoes, and more especially to the work-supports of such machines.

In a well known apparatus for effecting the temporary attachment of heels to shoes in which are lasts, the shoe and heel are supported upon their tread-surfaces and clamped together by pressure applied to the crown of the last-cone. To allow the direction of the clamping force to be effective to hold the heel in the desired position against the heel-seat, the support for the forepart is made adjustable as to height. This may so tip the heel, that the forward portion of the tread will be raised from its support, leaving only the rear edge in contact with the supporting surface. Under these conditions, the applied pressure may deform this edge. An object of my invention is to obtain in an effective manner an equalization of the pressure over the heel-tread. To attain this end, I combine with a member by which clamping pressure is applied, a tread-support for the work having not only a plate variable in position beneath the forepart of the shoe, but also a second plate mounted to move upon the support and upon which the heel-tread may rest, there being means to secure this second plate in definite angular positions with respect to the plane of the forepart-plate. With such a relation established, it may be made certain that, regardless of the direction of application of pressure to the work, the tread-surface of the heel will bear uniformly upon its plate without danger of mutilation. The adjustment of the heel-plate is preferably attained by mounting it to rock upon the support, as by an arcuate projection seated in a complementary recess, and movable by a screw connected to the plate and actuated by a nut threaded upon it and rotatable in the support. The screw may extend toward the forepart-plate, and the nut lie beneath the raised shank of the shoe, where it is readily accessible.

In the accompanying drawing,

Fig. 1 shows in side elevation the work-supporting portion of a heel-attaching machine embodying one form of my invention; and

Fig. 2 is a fragmentary top plan view of the heel-support.

At 10 appears the stem by which there is carried upon the frame F of a fastening-inserting machine the base 12 of a work-support A, the work, in the present instance, consisting of a shoe S upon a last L and a heel H, which is to be attached to the heel-seat of the shoe. The attachment may be effected in the customary manner, by operating through a passage s, extending

through the cone of the last, a drill to form a bore through the heel-seat of the shoe into the heel, and then inserting through this bore a long temporary screw, which engages the heel at its point and bears at its head upon the crown of the last-cone. The work is clamped upon the support, to maintain the shoe and heel firmly in the correct relation for the attachment, by a lever 14, which engages the cone of the last and is actuated by an unillustrated treadle mechanism.

The work-support proper is shown at 16, it carrying means to receive contact of the tread-surfaces of said work. It is pivoted at 18 upon the base 12 and adjustable as to angle by a wedge 20, which may be drawn between the support and base. This permits the operator to so position the work, that the passage s in the last will be located conveniently for the operations to be performed. The support carries a plate 22, upon which the forepart of the shoe may rest. A shank 24, depending from the plate, lies within a bore in the support, it being adjustably fixed therein by a set-screw 26. This adjustment of the forepart-plate is commonly employed to cause both the forepart of the shoe and the heel to tread uniformly upon the support. It is also utilized to so present the crown of the last-cone to the clamping lever 14, that the line along which pressure is applied will lie at or near the breast of the heel, tending to hold this firmly up to the breast-cut in the sole. The heel is also maintained at this time against rearward displacement by the usual back-stop 30, vertically adjustable upon the base. As the forepart-plate is raised for the last-stated purpose, and to attain the desired line of pressure for heels of some heights, as those of the Cuban type, the heel will be tilted back, so that, if its tread-end engages an unvarying surface of the support 16, its forward portion will be raised clear of the support, leaving contact only at the rear edge. Upon the application of pressure to the last-cone by the lever 14, this edge may be crushed and the heel thus deformed.

To prevent the above-indicated result, I arrange a heel-tread-plate 32 to rock longitudinally of the support 16. At the underside of this plate is an arcuate lug 34 fitting within a complementary recess 36 in the support. The common center of curvature of the lug and the recess lies in the heel-engaging surface of the plate. Longitudinally of the support the lug is divided, and pivoted to it, between the sections in vertically elongated openings 38, is a threaded rod 40. This rod extends forwardly through a depression in

the support, until, at a point beneath the shank of the shoe S, it receives an elongated cylindrical nut 42 having an enlarged head 43. This head is rotatable in a recess 44 in the support, but is held against axial movement by the recess-walls. The upper portion of the head projects above the support, so it may be manipulated by the operator, interference by the work being avoided by the location of the nut at the raised shank of the shoe. Upon turning the nut, the rod 40 will be shifted longitudinally, and, by its connection below the center of curvature of the lug 34, will rock the plate 32 in its depression. The pivot of the rod is capable of shifting in the openings 38 to accommodate itself to the variations in the angular position of the plate. The upper surface of the plate may thus be caused to lie parallel to the tread-face of the heel, whatever adjustments of the forepart-plate 22 may have been made, and clamping pressure applied by the lever 14 will be so distributed that there will be no deformation of the heel-edge. Moreover, the heel-plate will be locked as adjusted, so whatever may be the direction of clamping pressure, it cannot tilt the plate to destroy the parallel relation between said plate and the tread-surface of the heel.

Having described my invention, what I claim as new and desire to secure by Letters Patent of the United States is:

1. In a machine for inserting a fastening through a passage in a last within a shoe and into an applied heel, a tread-support for the work, a plate variable in position upon the support and upon which the forepart of the shoe may rest, a second plate mounted to move upon the support and upon which the tread-surface of the heel may rest, means for securing the heel-plate in different angular positions with respect to the plane of the forepart-plate, and movable clamping means for engagement with the cone of the last.

2. In a machine for inserting a fastening through a passage in a last within a shoe and into an applied heel, a base, a tread-support pivoted upon the base about an axis substantially parallel to the tread-surface of a supported shoe, means arranged to vary the angular position of the support, a plate variable in position upon the support and upon which the forepart of the shoe may rest, a second plate mounted to rock

upon the support and upon which the heel may rest, means for securing the heel-plate in different angular positions in accordance with the positions of the tread-support and forepart-plate, and a movable clamping member for engagement with the cone of the last.

3. In a machine for inserting fastenings for attaching heels to shoes, a tread-support for the work, a plate variable in position upon the support and upon which the forepart of the shoe may rest, a second plate mounted to rock upon the support and upon which the heel may rest, a screw connected to the second plate, and a nut threaded upon the screw and rotatable in the tread-support.

4. In a machine for inserting fastenings for attaching heels to shoes, a tread-support for the work, a plate variable in position upon the support and upon which the forepart of the shoe may rest, a second plate upon which the heel may rest and having an arcuate projection seated in a complemental recess in the support, a threaded rod pivoted to the projection, and a nut upon the rod rotatable in a recess in the support.

5. In a machine for inserting fastenings for attaching heels to shoes, a tread-support for the work, a plate variable in position upon the support and upon which the forepart of the shoe may rest, a second plate upon which the heel may rest and having a divided arcuate projection seated in a complemental recess in the support and provided with elongated openings, a threaded rod pivoted in the openings and extending forwardly in a depression in the support, and a nut upon the rod rotatable in a recess in the support.

6. In a machine for inserting fastenings for attaching heels to shoes, a tread-support for the work, a plate variable in position upon the support and upon which the forepart of the shoe may rest, a second plate upon which the heel may rest and having an arcuate projection seated in a complemental recess in the support, a threaded rod pivoted to the projection and extending toward the forepart-plate, and a nut upon the rod rotatable in the support between the forepart-plate and the heel-plate and beneath the shank of the supported shoe.
